(57) **CLAIM**

The ornamental design for a kayak rack, as shown and described.

DESCRIPTION

FIG. 1 is a top, front, right side perspective view of a first embodiment of kayak rack, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, right side perspective view showing the kayak rack in FIG. 1 with its top horizontal rod removed and the middle rod raised;

FIG. 10 is a top, front, right side perspective view showing the kayak rack in FIG. 1 in detached state;

FIG. 11 is an enlarged view of the portion 11 in FIG. 1;

FIG. 12 is an enlarged view of the portion 12 in FIG. 1;

FIG. 13 is an enlarged view of the portion 13 in FIG. 1;

FIG. 14 is an enlarged view of the portion 14 in FIG. 2;

FIG. 15 is an enlarged view of the portion 15 in FIG. 3;

FIG. 16 is an enlarged view of the portion 16 in FIG. 5;

FIG. 17 is an enlarged view of the portion 17 in FIG. 7;

FIG. 18 is an enlarged view of the portion 18 in FIG. 8;

FIG. 19 is a top, front, right side perspective view of a second embodiment of kayak rack, showing my new design;

FIG. 20 is a bottom, rear, left side perspective view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom plan view thereof;

FIG. 27 is a top, front, right side perspective view of a third embodiment of kayak rack, showing my new design;

FIG. 28 is a bottom, rear, left side perspective view thereof;

FIG. 29 is a front elevational view thereof;

FIG. 30 is a rear elevational view thereof;

FIG. 31 is a left side elevational view thereof;

FIG. 32 is a right side elevational view thereof;

(Continued)

FIG. 33 is a top plan view thereof; and,
FIG. 34 is a bottom plan view thereof.

The evenly dashed broken lines illustrate portions of the kayak rack and form no part of the claimed design. The unevenly dashed broken lines define the boundaries of enlarged views and form no part of the claimed design.
